CLAIM

The ornamental design for a glass bottle, as shown and described.

DESCRIPTION

FIG. 1 is a side sectional view of the ornamental design for a glass beverage bottle according to the present invention. FIG. 2 is a front sectional view of the ornamental design for a glass beverage bottle according to the present invention. FIG. 3 is a side sectional view of the ornamental design for a glass beverage bottle according to the present invention. FIG. 4 is a top view of the ornamental design for a glass beverage bottle according to the present invention.

FIG. 5 is a bottom view of the ornamental design for a glass beverage bottle according to the present invention.

FIG. 6 is a side perspective view of the ornamental design for a glass beverage bottle according to the present invention.

FIG. 7 is a front perspective view of the ornamental design for a glass beverage bottle according to the present invention; and,

FIG. 8 is a side perspective view of the ornamental design for a glass beverage bottle according to the present invention.
